United States Patent Office

Des. 227,299

Patented June 12, 1973

227,299

VOTING MACHINE

Michael Terrance Moldovan, Jr., Lakewood, N.Y.,
assignor to AVM Corporation, Jamestown, N.Y.

Filed June 28, 1971, Ser. No. 157,781

Term of patent 14 years

Int. Cl. D10—99

U.S. Cl. D52—6 R

Fig. 1.

Fig. 2.

Fig. 3.

Fig. 4.

Fig. 5.

FIG. 1 is a front perspective view of a voting machine showing my new design;

FIG. 2 is a front elevational view thereof;

FIG. 3 is a rear elevational view thereof;

FIG. 4 is a left side elevational view thereof; and

FIG. 5 is a right side elevational view thereof.

I claim:

The ornamental design of a voting machine, substantially as shown and described.
